UNITED STATES PATENT OFFICE.

CHARLES H. HOYT, OF BEVERLY, MASSACHUSETTS, ASSIGNOR TO UNITED SHOE MACHINERY CORPORATION, OF PATERSON, NEW JERSEY, A CORPORATION OF NEW JERSEY.

FASTENING MECHANISM.

Original application filed July 23, 1921, Serial No. 487,098. Divided and this application filed November 17, 1922. Serial No. 601,594.

To all whom it may concern:

Be it known that I, CHARLES H. HOYT, a citizen of the United States, residing at Beverly, in the county of Essex and State 5 of Massachusetts, have invented certain Improvements in Fastening Mechanism, of which the following description, in connection with the accompanying drawings, is a specification, like reference characters 10 on the drawings indicating like parts in the several figures.

This invention relates to fastening mechanism, and is herein shown as embodied in fastening mechanism particularly designed 15 for use in a machine for lasting the heel ends of shoes described and claimed in my co-pending application Ser. No. 487,098, filed on July 23, 1921, of which this application is a division. It will be recognized, however, 20 that the invention is not limited to use in machines of that particular type but is of general applicability to various kinds of machines and apparatus.

The invention provides in fastening mechanism comprising a holder or throat member which positions or guides the fastening, a novel organization including provision for moving said holder or throat member toward and from the work. The construction 25 herein shown comprises a tack holder so controlled as to be moved yieldingly toward the work in response to the operative movement of the tack driving means and to be moved away from the work by the 30 retractive movement of the driving means. Such an organization may have various objects in view, for example to insure better control of the fastening by positioning the holder close to the work when the fastening 35 is driven or to apply pressure to the work through the holder, while affording at other times sufficient clearance between the holder and the work to permit other operations to be performed; and as applied to a heel seat 40 lasting machine, as herein shown, an important object is to afford ample clearance for the operation of the wipers prior to the upper fastening operation and thereafter to position the tack holder sufficiently close 45 to the work to insure proper control of the tack without the necessity for using a longer tack than is desirable.

The above and other features of the invention, including certain details of construc-

tion and combinations of parts, will now be 55 more particularly set forth by reference to the accompanying drawings and pointed out in the claims.

In the drawings,

Fig. 1 is a view, partly in elevation and 60 partly in vertical section, of fastening mechanism embodying the present invention, showing this mechanism in operative relation to other parts of a machine of the type shown and described in my copending application;

Fig. 2 is a view similar to Fig. 1 showing the parts in a different position;

Fig. 3 is a vertical section through one 70 of the tack throats or holders detached, and

Fig. 4 shows parts of the tack holder in disassembled relation.

In the use of the invention as a part of the organization of the machine shown in my copending application a last *a* with the 75 shoe materials mounted thereon is positioned upon a work support (not shown) and the heel end of the shoe is embraced and held by a heel band 2 for the operation of heel seat lasting wipers 4 which are moved 80 inwardly and outwardly over the heel seat to lay the margin of the upper over the insole. For fastening the margin of the upper to the insole after the wipers have been partially retracted from their innermost position over the heel seat, the machine is provided with a plurality of fastening mechanisms for driving lasting tacks in different locations about the end of the shoe, 85 only one of such mechanisms being herein 90 shown as an illustration of the present invention. Mounted for positioning movement above the wipers is a tack block 6 provided with one or more cylindrical openings extending upwardly in parallel relation to the directions of movement of the tack driving means to serve as guiding means for one or more tack throats or holders, one of such tack holders being shown detached in 95 Figs. 3 and 4. The tack holder or throat member comprises a tube 8 adapted to slide lengthwise in the opening in the block 6 and adapted to receive within it a tack driver 10. At its lower end the tack holder 100 is provided with a pair of tack fingers 14 which have complementary tack receiving recesses and are provided with cylindrical bearing portions 16 to turn in corresponding

105

transverse bearings 18 on the lower end portion of the tube member 8, the tack fingers being guided in their opening and closing movements between lugs 20 adjacent to the bearings. To hold the tack fingers normally closed, springs 22 are provided, as illustrated in Fig. 3. The tube 8 is provided with a slot 24 arranged to register with a corresponding slot in the block 6 through which tacks are fed from a tack tube 26 leading from the usual tack separator.

The tack driver 10 is carried by a driver bar 28 which is movable lengthwise in a guide member 30, the driver bar being connected at its upper end to an upwardly and downwardly movable driver head 32 the construction and operation of which are more fully set forth in my copending application. A spring 34 acts between the upper end of the driver bar 28 and a pin 36 on the guide member 30 to assist in imparting upward or retractive movement to the driver bar. It will be understood that when the member 32 is moved downwardly it imparts operative movement to the driver bar and the driver 10 to drive the tack.

The tack holder is positioned initially with its tack fingers 14 sufficiently elevated to be clear of the wipers 4 in their movements over the heel seat, as shown in Fig. 1, and in the tack driving operation is moved downwardly toward the heel seat, for example to the position illustrated in Fig. 2. For the purpose of such control of the tack holder there is mounted in a guideway in the member 30 at one side of the driver bar for movements in directions parallel to the directions of movement of the driver bar a slide 38 which has projecting downwardly therefrom a plate 40 the lower end of which is bent into position to enter a slot 42 formed in one side of the tube 8. The slide 38 is pressed downwardly by means of a spring 44 and a plunger 46 which are mounted within a socket in the slide, the plunger bearing upwardly against the wall of the recess in the member 30 in which the slide 38 is mounted. The slide 38 has thereon a projection 48 which extends into a slot formed in the driver bar 28 and in the upward or retractive movement of the driver bar is engaged by a shoulder 50 on said bar to impart upward movement to the slide 38 and thus to move the tack holder upwardly to the position illustrated in Fig. 1. When the driver bar receives its operative movement it releases the slide 38 and the spring 44 acts to force the slide and the tack holder downwardly with the driver bar to position the tack fingers nearer to the work in the driving of the tack. In the construction herein shown such downward movement of the tack holder is limited by engagement of a projection 52 on the slide 38 with a shoulder 54 formed on the member 30. The tack holder is thus

moved yieldingly toward the work, under control of the driver bar, by the action of the spring 44 and is moved away from the work by positive engagement of the driver bar with the projection 48. It will be understood that if the tack block 6 has a plurality of tack holders mounted therein, corresponding to a plurality of tack drivers carried by the driver bar 28 for driving a group of tacks simultaneously, the plate 40 will be so shaped as to connect with the several tack holders for moving them simultaneously toward or from the work.

While the invention is herein illustrated by reference to mechanism designed for driving fastenings in the form of tacks, it will be understood that the invention is not limited to the use of fastenings of this particular character.

Having thus described the invention, what I claim as new and desire to secure by Letters Patent of the United States is:

1. In mechanism of the class described, a member mounted for reciprocatory movement to drive a fastening and then to retract from the work, a holder for the fastening mounted for movement toward and from the work, a slide mounted independently of said holder at one side of the driving member and connected to the holder for moving it toward and from the work, and means for rendering said driving member effective in its retractive movement to operate said slide and thereby move said holder away from the work.

2. In mechanism of the class described, a member mounted for reciprocatory movement to drive a fastening and then to retract from the work, a holder for the fastening mounted for movement toward and from the work, a slide guided independently of said holder and controlled by the driving member, an operating connection between said holder and slide, and a spring for operating said slide to move the holder toward the work when the driving member receives its operative movement.

3. In mechanism of the class described, a member mounted for reciprocatory movement to drive a fastening and then to retract from the work, a holder for the fastening mounted for movement toward and from the work, a slide mounted independently of said holder and connected to the holder for moving it toward and from the work, means for rendering the driving member effective to operate said slide to retract the holder from the work, a spring for moving the holder toward the work when the driving member receives its operative movement, and means operative independently of the work to limit the movement of the holder toward the work.

4. In mechanism of the class described, a tack driver, a tack holder comprising tack-

retaining fingers movable toward and from the work lengthwise of said driver, a driver bar, a guide for said driver bar having a recess therein, a member separate from the 5 tack holder movably mounted in said recess, a connection between said member and the tack holder, and means for rendering the driver bar effective on said member to retract the tack holder from the work.

10 5. In mechanism of the class described, a tack block, a tack holder comprising tack fingers and a tubular support for said fingers slidable in the tack block toward and from the work, a reciprocatory tack driving 15 member, and mechanism connected to said tubular support and controlled by said tack driving member for moving the tack holder toward and from the work.

6. In mechanism of the class described, a 20 tack driver, a tack holder movable toward and from the work lengthwise of said driver, a driver bar, a guide for said driver bar having a recess therein, a slide movably mounted in said recess independently of the 25 tack holder, a connection between said slide and the tack holder, a spring acting on said slide to move the tack holder toward the work, and means on the driver bar for engaging the slide to retract the tack holder 30 from the work.

7. In mechanism of the class described, a 35 throat member, a driver, said throat member being movable in directions lengthwise of the driver toward and from the work, a spring mounted independently of the driver and arranged to move the throat member toward the work, and a device movably guided at one side of said driver independently of the throat member and arranged to 40 hold the throat member normally retracted from the work and when the driver is operated to release said member to the action of its spring.

8. In mechanism of the class described, a 45 throat member, a driver, said throat member being movable in directions lengthwise of the driver toward and from the work, a reciprocatory driver bar for operating the

driver, said driver bar having a shoulder thereon, and a member for controlling said 50 throat member movably mounted independently of the throat member at the side of the driver bar and arranged to be engaged by said shoulder to move the throat member away from the work as the driver is 55 retracted and to be released by said shoulder to permit the throat member to move toward the work as the driver is operated.

9. In mechanism of the class described, a tack holder, a driver, said tack holder 60 comprising a slotted tubular member movable in directions lengthwise of the driver toward and from the work, a driver bar for operating said driver, and a device engaging 65 said tubular member in its slot and controlled by said driver bar for moving said tack holder toward and from the work.

10. In mechanism of the class described, a tack holder, a driver, said tack holder being movable in directions lengthwise of the 70 driver toward and from the work, a driver bar for operating said driver, a slide mounted independently of the driver bar and tack holder and connected to said tack holder, said slide being arranged to be engaged by the driver bar to withdraw the tack holder from the work, and a spring arranged 75 to operate said slide to move the tack holder toward the work.

11. In mechanism of the class described, 80 a tack holder, a driver, said tack holder being movable in directions lengthwise of the driver toward and from the work, a driver bar for operating said driver, a slide connected to said tack holder and having an 85 abutment arranged to be engaged by a shoulder on the driver bar to withdraw the tack holder from the work, means providing a guideway for said slide at the side of the driver bar, a spring for operating said slide 90 to move the tack holder toward the work, and a stop for limiting movement of the slide under the action of said spring.

In testimony whereof I have signed my name to this specification.

CHARLES H. HOYT.
